UNITED STATES PATENT OFFICE.

ALAN R. FERGUSSON, OF BUFFALO, NEW YORK, ASSIGNOR TO A. R. FERGUSSON MFG. CORP., OF BUFFALO, NEW YORK, A CORPORATION OF NEW YORK.

ICE SKATE.

Application filed January 18, 1927. Serial No. 161,920.

This invention relates to an ice skate and has for its object the production of a skate which is comparatively low in cost, very strong and durable and capable of being readily adjusted as to size for fitting shoes varying in length and breadth within reasonable limits, and thereby enabling a dealer to furnish skates suitable for use by boys and men without requiring him to carry in stock an undue number of sizes to supply the demands of the trade as has been necessary heretofore.

In the accompanying drawings:

Fig. 1 is a side elevation of one form of skate embodying my improvements. Figure 2 is a top plan view thereof. Figures 3 and 4 are vertical transverse sections taken on the correspondingly numbered lines in Fig. 1. Figures 5, 6 and 7 are horizontal sections taken on the correspondingly numbered lines in Fig. 1. Figure 8 is a vertical longitudinal section taken on line 8—8, Fig. 4. Figure 9 is a side elevation showing a modified form of my invention as compared with the structure shown in Figs. 1—8. Figure 10 is a vertical cross section taken on line 10—10, Fig. 9. Figure 11 is another form of the skate blade or runner containing my improvements. Figures 12 and 13 represent cross sections of different forms of the runner or blade suitable for use in the skate made in accordance with my invention.

Similar characters of reference indicate like parts in the several views of the drawings.

Referring to the construction shown in Figs. 1—8, the numeral 20 represents the runner or blade of the ice skate which is preferably constructed from a bar of steel or other high grade material which is of substantially uniform shape in cross section so that the same can be rolled or otherwise formed in comparatively long sections and cut into short sections of the required length suitable for use as skate runners. The runners may be of various forms so far as their lengthwise appearance is concerned, for example, the body of the runner may be straight and the front end 21 slightly turned up, as shown in Fig. 1, or the same may be curved so as to be low at the middle and high at the front and rear ends and thus serve as rocker skates heretofore in common use.

Although the runner may be of any approved form in cross section, that shown in Figs. 1—8 is of oblong rectangular form in

cross section with the wide faces arranged vertically on opposite sides of the runner.

Mounted on the front and rear parts of the runner are front and rear supports 22, 23, for the shoe of a skater's foot. Each of these supports is preferably constructed of L-shaped members or sections, each of which is stamped out of comparatively thin metal which is low in cost so as to form a vertical part or web 24, the lower end of which is connected with the runner and a horizontal part or plate 25 which projects laterally from the upper end of the vertical part. The two members or sections of each support are assembled with their webs placed side by side to form a pedestal or standard while the horizontal plates together form a platform. These two L-shaped sections may be connected in any suitable manner, for example, by electric spot welding, riveting or the like, but preferably by providing the web of one section with locking openings 26 at its upper end and stamping locking lips 27 out of the upper end of the web of the companion section and extending these lips through said openings 26 and clinching the same against the outer side of the respective web, as shown in Figs. 1 and 4. In the case of the front support the front ends 28 of the platform plates are turned upwardly to fit the front or toe portion of a shoe, and in the case of the rear support the rear ends of the platform plates are provided with upwardly projecting heel stop flanges 29, as shown in Figs. 1, 2, 3 and 4. For securing greater strength one of these heel stop flanges laps laterally over the other, as shown at 30 in Fig. 2.

In order to stiffen the pedestals or standards of the supports and thus permit of using lighter material and also to improve appearance of the same, the webs of each support are provided at their front and rear edges with outwardly projecting edge beads or ribs 31, 31, and intermediate of the latter with central beads or ribs 32.

The lower parts of the webs forming the pedestal of each support are spread apart and straddle the upper part of the runner. If desired, one or the other of the supports may be permanently secured to the runner and the other support may be capable of adjustment lengthwise of the runner in order to adapt the distance between the supports to the length or size of the shoe intended to receive the skate. As shown in Figs. 1, 3 and 5

the lower ends of the two webs of the front support are secured to opposite sides of the runner by rivets 33. The rear support is represented in Figs. 1, 4, 5 and 8 as capable of 5 adjustment lengthwise of the runner by constructing the lower ends of the vertical webs of this pedestal in the form of inturned hooks 34, the beaks of which engage longitudinal grooves 35 on opposite sides of the runner 10 and are capable of sliding lengthwise therein for adjusting the rear shoe support toward and from the front shoe support. After the rear support has been shifted into the desired position relative to the front support, 15 the rear support may be fastened in place by a clamping bolt 36 passing through the webs of the pedestal immediately above the hooks thereof, as shown in Figs. 1 and 4. The nut 37 of this clamping bolt is preferably arranged close to the adjacent pedestal hook, 20 as shown in Figs. 1 and 4, so that the same will strike and be incapable of turning while tightening or loosening this bolt by a screw driver applied to the head of the same, thereby 25 facilitating the adjustment of the skate.

Means are provided for positively interlocking the heel support with the runner so as to prevent the adjustment between the toe and heel supports from being disturbed when 30 the skate is subjected to severe blows, shocks or strains. The preferred construction of these interlocking means consists of longitudinal rows of upright corrugations or serrations 38 arranged on opposite sides of the runner above the hook receiving grooves therein and corresponding longitudinal rows of upright corrugations 39 arranged on the inner sides of the hooks and adapted to interlock with the corrugations of the runner. 35 Upon loosening the clamping bolt 36 the hooks can be spread apart sufficiently to disengage the corrugations of the same from those of the runner and after the rear support has been moved forwardly or backwardly 40 by the required extent the same will be positively held there upon tightening the clamping bolt 36 and re-engaging the co-operating corrugations.

Instead of taking hold of the rear support 50 and sliding the same toward and from the front support this is preferably accomplished by an adjusting rod or screw 40 arranged lengthwise above the runner or blade and operatively connected with the supports. In the 55 construction shown in the drawings the adjusting rod is provided at its front end with a head 41 which turns in a socket or bearing 42 formed between the opposing rear parts of the webs of the front support, as shown in 60 Figs. 1 and 6, and the rear end of the adjusting screw is provided with an external screw-thread 43 which works in an internally threaded opening 44 formed between the opposing sides of the webs of the rear support, as shown in Figs. 1, 4, 6 and 8. Upon 65

turning the adjusting rod the same is held against lengthwise movement on the front support thereby compelling the rear support to move lengthwise on the runner. Turning of the rod is preferably facilitated by providing its central part with a flattened wing 70 45 which may either be grasped by the fingers or receive a wrench.

Any suitable means may be employed for attaching the supports to the toe and heel portions of the shoe. If the skate is to be permanently connected with the shoe the platform plates may be provided with holes 75 46 adapted to receive screws which enter the sole and heel of the shoe. If, however, it is desired to quickly attach the skate to the shoe and remove the same therefrom it is preferable to employ the clamping means which are shown in the drawings in connection with the platforms of the front and rear supports. 80 Each of these clamping means is constructed as follows: On the outer side edge of each platform plate the same is provided with a depending guide ear 47 which is formed integrally with this plate. Sliding transversely in each of these guide ears is a clamping bar 48 which is provided at its outer end with an upwardly and inwardly projecting clamping jaw 49 while its inner end is provided with a downwardly projecting adjusting lug 19 and an adjusting screw rod having its central part journaled on the pedestal of the support and provided on its opposite ends with right and left screw threads 50 working in threaded openings in the adjusting lugs. Turning of the adjusting screw rod or shaft is preferably effected by terminating one end of the same in a square shank 51 which is adapted to receive a suitable key and thus permit of engaging and disengaging the jaws of the clamping bars with opposite sides of the shoe sole. The clamping screw is preferably journaled on the pedestal of the front support by passing the body of this screw through the large part 52 of a key hole slot in the webs of the front pedestal and then moving the adjusting screw laterally so that the contracted neck 53 on the central part of the same enters the narrow part 54 of the keyhole slot, as shown in Figs. 100 5 and 8, whereby the adjusting screw will be free to turn but held against lengthwise motion.

In case the skater has weak ankles it is customary to apply a strap to the ankle and the rear part of a skate. To permit of doing this is the present skate a slot 60 is formed in the rear upper parts of the webs of the heel support through which the ankle supporting strap may be passed. The metal displaced during the formation of the openings in these webs to produce this slot is, however, bent laterally outward at the upper sides of these openings so as to form bearing wings 61 which present a wide surface for engagement with the skate strap and thereby prevent cut- 105 110 115 120 125 130 135

ting and undue wearing of the same, when drawn taut. If desired, the adjusting screw may be mounted on the pedestal of the support by providing the central part of the same with a collar 55 which is confined in a bearing 56 formed between the two webs of a pedestal, as shown in Fig. 10.

In the modified form of my improved skate shown in Fig. 9, both the front and rear supports are mounted on the runner in the manner described with reference to the rear support shown in Figs. 1-8, so that both the front and rear supports can be adjusted lengthwise on the runner to suit the length of the shoe on which the skate is to be worn or to meet other conditions or requirements.

When only the rear support is made adjustable lengthwise of the runner then the hook groove 35 need extend only along the rear part of the runner, as shown in Fig. 1. If, however, the front and rear supports are both made adjustable on the runner then the hook grooves 35 may either extend the full length of the runner, as shown in Fig. 9, or the same may be formed the required length on the front and rear parts of the runner, as shown in Fig. 11.

Instead of making the runner of rectangular form in cross section, as shown in Figs. 3, 4 and 10, the same may be otherwise constructed. For example, the same may be of T-form in cross section, as shown at 59 in Fig. 12, or the same may be provided with an upper wide head 57, and a downwardly enlarging stem 58, as shown in Fig. 13.

I claim as my invention:

1. An ice skate comprising a runner, shoe supporting means including L-shaped members having vertical parts engaging their lower ends with opposite sides of the runner and horizontal parts projecting laterally from the upper ends of said vertical parts, said horizontal parts being provided at their outer ends with downwardly projecting guide ears, and means for clamping the shoe to said supporting means including clamping bars guided in said ears and provided at their outer ends with jaws adapted to engage opposite sides of the shoe, and adjusting means connecting said bars.

2. An ice skate comprising a runner, shoe supporting means including L-shaped members having vertical parts engaging their lower ends with opposite sides of the runner and horizontal parts projecting laterally from the upper ends of said vertical parts, said horizontal parts being provided at their outer ends with downwardly projecting guide ears, and means for clamping the shoe to said supporting means including clamping bars guided in said ears and provided at their outer ends with jaws adapted to engage opposite sides of the shoe, and at their inner ends with downwardly projecting adjusting lugs, and a rotary adjusting rod having its central

part mounted on said vertical parts and provided at its opposite ends with right and left screw threads working in said lugs.

3. An ice skate comprising a runner and shoe supporting means including L-shaped members having vertical parts engaging their lower ends with opposite sides of said runner and horizontal parts projecting laterally from the upper ends of said vertical parts, one of said members being provided with a locking opening and the other of said members having a locking lip formed thereon which extends through said opening and is clinched for holding the respective members together.

4. An ice skate comprising a runner provided on its opposite sides with longitudinally extending grooves, and a foot support including members having hooks at their lower ends which engage with said grooves, and means for connecting said members.

5. An ice skate comprising a runner and shoe supporting means including L-shaped members having vertical parts engaging their lower ends with opposite sides of said runner and horizontal parts projecting laterally from the upper ends of said vertical parts, said members being provided with corresponding openings for receiving a strap.

6. An ice skate comprising a runner and shoe supporting means including L-shaped members having vertical parts engaging their lower ends with opposite sides of said runner and horizontal parts projecting laterally from the upper ends of said vertical parts, said members being provided with corresponding openings for receiving a strap, and said openings being formed by displacing material from said supports to produce laterally projecting bearing wings at the upper edges of said openings.

7. An ice skate comprising a runner and separate shoe supporting means including L-shaped members having vertical parts engaging their lower ends with opposite sides of said runner and horizontal parts projecting laterally from the upper ends of said vertical parts, said members being provided at their rear ends with upwardly projecting heel stop flanges.

8. An ice skate comprising a runner, and shoe supporting means including L-shaped members having vertical parts engaging their lower ends with opposite sides of said runner, horizontal parts projecting laterally from the upper ends of said vertical parts, and heel stop flanges projecting upwardly from the rear ends of said horizontal members and lapping laterally one over the other.

9. An ice skate comprising a runner provided on its opposite sides with longitudinal grooves, and a shoe support which is adjustable lengthwise on said runner and provided at its lower end with hooks engaging

with said grooves, and fastening means for clamping said hooks against opposite sides of said runner.

10. An ice skate comprising a runner provided on its opposite sides with longitudinal grooves, a shoe support including L-shaped members having vertical parts provided at their lower ends with hooks engaging with said grooves and slideable lengthwise therein, 10 and horizontal parts projecting laterally from the upper ends of said vertical parts, and clamping means connecting said upright parts.

11. An ice skate comprising a runner provided on its opposite sides with longitudinal grooves, a shoe support including L-shaped members having vertical parts provided at their lower ends with hooks engaging with said grooves and slideable lengthwise therein, 15 and horizontal parts projecting laterally from the upper ends of said vertical parts, and clamping means connecting said upright parts, the outer sides of said runner being provided with corrugations and the inner 20 sides of said hooks being provided with corrugations interlocking with the corrugations of said runner.

12. An ice skate comprising a runner, a front support mounted on the front part of 30 said runner and adapted to support the toe portion of the shoe, a rear support mounted on the rear part of the runner and adapted to support the heel portion of the shoe, said supports being relatively adjustable lengthwise of the runner, and an adjusting screw 35 connected at its opposite ends with said supports.

13. An ice skate comprising a runner, a front support mounted on the front part of 40 said runner and adapted to support the toe portion of the shoe, a rear support mounted on the rear part of the runner and adapted to support the heel portion of the shoe, said supports being relatively adjustable lengthwise of the runner, one of said supports having a socket and the other support having a threaded opening, and an adjusting screw having a head at one end arranged in said socket and a thread at its opposite end which 45 engages said threaded opening. 50

14. An ice skate comprising a runner provided on its opposite sides with longitudinal grooves, a front support mounted on the front part of said runner and adapted to support the toe portion of a shoe, a rear support mounted on the rear part of the runner and adapted to support the heel portion of a shoe, each of said supports including members having upright parts which engage their lower ends with opposite sides of said runner, the members of one support being secured to said runner and the members of the other support being slideable in said 55 grooves, and one of said supports having its members constructed to form a socket between them and the other support having its members constructed to form a threaded opening between them, and an adjusting rod having a head at one end which turns in said 60 socket and a screw thread at its opposite end which works in said threaded opening. 65 70

In testimony whereof I affix my signature.

ALAN R. FERGUSSON.
